(57) **CLAIM**

I claim the ornamental design for a mobile phone, as shown and described.

DESCRIPTION

FIG. 1 is a front, top, and left side perspective view of our new design for a mobile phone;

FIG. 2 is a perspective view of our new design with the keypad slid shut;

FIG. 3 is a front elevation view of our new design;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line showings are for illustrative purposes only and form no part of the claimed design.
